UNITED STATES PATENT OFFICE.

EDWARD B. FEASTER, OF BOSTON, MASSACHUSETTS.

FLIER AND METHOD OF MAKING THE SAME.

1,393,356.

Specification of Letters Patent.

Patented Oct. 11, 1921.

Application filed September 7, 1920. Serial No. 408,557.

To all whom it may concern:

Be it known that I, EDWARD B. FEASTER, of Boston, county of Suffolk, and State of Massachusetts, have invented an Improvement in Fliers and Methods of Making the Same, of which the following description, in connection with the accompanying drawings, is a specification, like characters on the drawings representing like parts.

10 This invention relates to a flier for use on roving and twisting machines and to a novel method of making the same.

The invention has for its object to produce in a novel manner as will be described 15 a flier of novel construction, which has the appearance of the standard drop forged flier now commonly used, and also has the desirable features of the latter, and possesses in addition advantageous features, as will be 20 described, whereby a superior flier may be provided at a minimum cost and in a minimum time.

To this end the flier is provided with a solid metal member which forms one arm of 25 the flier, and a hollow sheet metal member which forms the other arm of the flier and is firmly connected with the solid metal member and reinforced by the latter to withstand the strain of centrifugal force while in use. 30 The flier is further provided with a hub of novel construction, for the reception of the spindle.

These and other features of this invention will be pointed out in the claims at the end 35 of this specification.

Figure 1 is a front elevation of a flier embodying this invention and produced in a novel manner.

Fig. 2, a side elevation of the flier shown 40 in Fig. 1 looking toward the left.

Fig. 3, an elevation of the solid metal member shown in Fig. 1.

Fig. 4, an elevation of the hollow sheet metal member shown in Fig. 1.

45 Fig. 5, a plan view of Fig. 3.

Fig. 6, a section on line 6—6, Fig. 1, and Fig. 7, a section on line 7—7, Fig. 1.

Referring to the drawings, *a* represents the solid metal member, *b* the hollow sheet 50 metal member, *c* the hub, and *d* the key for engaging the spindle (not shown) but with which the hub *e* co-operates in a manner well understood. The solid metal member *a*, shown separately in Fig. 3, is preferably 55 forged from a steel rod or bar and is shaped to form an arm having a substantially

straight portion 10, preferably oval in cross section, and a curved upper portion 12, which latter is integral with a substantially flat center portion 13 forming a supporting 60 member for the hub *c*, and from which extends a shorter curved arm 14, of substantially the same curvature as the curved portion 12 and diametrically opposite thereto. The curved arm 14 is provided with a concaved outer surface 15 into which is fitted a correspondingly curved upper portion 16 of the hollow metal arm *b*, whose lower portion 17 is substantially straight and preferably 65 round in cross section.

The hollow metal arm *b* is made from a flat blank or piece of sheet metal, preferably cold rolled steel, which is provided with smooth upper and lower surfaces free from 70 scale, burs or the like.

The metal blank is curved at its upper end to conform to the curve of the shorter arm 14, and after being fitted to the arm 14, is electrically welded or otherwise firmly secured to the arm 14. At the same time the 80 sheet metal blank is welded to the shorter arm 14 of the solid member *a*, a lug 20 is also welded to the outer side of the blank at a suitable distance from the upper curved end thereof so as to co-operate with a lug 21 85 at the end of the shorter arm 14 to form a mounting for the usual presser employed with fliers and not herein shown, as its construction and operation are well understood.

After the sheet metal blank has been 90 welded to the shorter arm 14 as described, the blank is folded by suitable dies or other mechanism so as to bring the side edges of the blank in close proximity to each other to form the hollow arm *b* and provide the 95 latter with a longitudinally extended slot 25. The sheet metal blank is made of suitable shape and width to provide the hollow arm *b* with a larger or wider upper curved end portion, which decreases in size or diameter from its end 26 to the straight portion 17 of said hollow arm. In the present instance, the hollow arm *b* is located wholly on one side of the center or supporting portion 13 of the solid arm *a*, and is provided 105 with a finger 27 which projects beyond the open upper end 26 of the hollow arm and abuts against a shoulder 28 on the supporting portion 13 of the solid member, and is of substantially the thickness of said shoulder 110 so as to have its upper surface substantially flush with the upper surface of the

supporting portion 13, as shown in Fig. 1. While this construction may be preferred, it is not desired to limit the invention in this respect.

5 After the hollow arm *b* has been formed as described, the grooves or openings which are found between the hollow arm *b* and the side edges of the shorter arm 14 of the solid member *a*, may and preferably will be 10 filled with hard solder or other suitable material, which filling 30 is represented in Figs. 6 and 7, and by means of said filling a smooth external surface for the hollow arm *b* and solid arm 14 may be obtained.

15 After the solid and hollow arms *a*, *b* have been welded or otherwise firmly secured together, a hole 31 is drilled in the supporting portion 13 at the center of the flier, for the reception of the hub *c*, which is made from 20 solid stock on a screw machine or automatic lathe and therefore rapidly produced. The hub *c* is provided with a cylindrical lower portion 33 whose external diameter is substantially the same as that of the opening 25 31, and with a head 34 of larger diameter which forms an annular shoulder 35 which rests upon the upper surface of the supporting portion 13 of the solid member *a*.

The hub *c* may be threaded into the opening 31 and the threads rusted in or it may 30 be electrically welded or otherwise firmly secured to the bearing member 13. The hub *c* is preferably provided with a tapering bore 37, which gradually tapers from the 35 lower end of the hub to near the upper end thereof and with which communicates a smaller opening 38 in the upper end of the head 34 and a lateral opening 39, for the passage of the roving through the opening 40 38 into the head 34 and out therefrom through the lateral opening 39 into the hollow arm *b*, from which it passes out through the slot 25 at some portion of the length thereof in a manner well understood.

45 After the hub *c* has been fastened to the solid arm *a*, a hole or opening is broached or otherwise formed in the bearing portion 13 of the solid member *a* and in the hub *c*, for the reception of the key *d*, which engages 50 a slot in the upper end of the spindle (not shown), so that the latter may drive the flier in a manner well understood.

The shorter arm 14 of the solid member *a* is preferably made of greater thickness adjacent the bearing portion 13 and tapers toward the center of said arm, as shown in 55 Figs. 1, 3, 6 and 7, which increased thickness acts to reinforce the curved upper portion of the hollow member so as to enable 60 the hollow member to withstand the strain of centrifugal force at ordinary speeds of use, which usually ranges from 1000 to 1400 revolutions of the flier per minute.

The hollow sheet metal member *b* and the

solid member *a* are properly proportioned 65 so that in the finished flier, a perfect balance between the arms of the flier is obtained.

By welding the sheet metal blank to the solid member and welding the hub or lug 20 70 to the said blank before the latter is closed to form the hollow arm, any scale, burs or rough spots on the surface of the blank which ultimately forms the inner surface of the hollow arm, can be readily removed as 75 such scale, etc., are freely accessible to the workman.

It is prefererd to make the hollow member from cold rolled sheet steel as the latter is normally provided with a perfectly 80 smooth surface. It is also prefererd to use hard solder to fill the joints between the hollow member *b* and the edges of the shorter arm 14 of the solid member, as the heat required to melt the hard solder is not sufficient to cause scale to be formed on the inner or upper surface of the sheet metal blank, and if scale should be formed by application of too great a heat, it is accessible 85 and can be readily removed, as above pointed out.

Furthermore, the hard solder can be quickly ground off and polished, and the joint rendered invisible by nickel plating. It is prefererd to nickel plate or otherwise 95 treat the finished flier so as to prevent rusting, due to the operators handling the fliers with moistened hands, especially in warm climates.

The finished flier represented in Fig. 1 100 and composed of a solid metal member and hollow sheet metal member has substantially the same appearance as the solid one piece flier now imported into this country, and therefore is not open to objection by the 105 workmen who are usually foreigners and naturally would be prejudiced against fliers which differ radically in appearance and construction from those with which they are familiar.

Furthermore, the fliers embodying this 110 invention can be made in a minimum time and at a minimum expense, so that they can be provided in sufficient quantities and at such cost as to satisfy the demand for the 115 same.

In the present instance a preferred construction of flier is shown, but it is not desired to limit the invention to the particular construction shown.

The supporting member 13 is preferably 120 provided on its under surface on opposite sides of the center opening 31 with depressions or sockets 50 for the reception of molten metal which serves to secure the hub *c* to the supporting member and to strengthen the latter, especially so as to withstand the strains of centrifugal force.

The solid member *a* may be made as a single piece or of a plurality of pieces butt welded together.

Claims:

- 5 1. In a flier, in combination, a solid metal member comprising an arm having a substantially straight lower portion and a curved upper portion, a supporting member extended from said curved upper portion and a shorter curved arm extended from said supporting member and provided at its free end with a lug and having its portion near said supporting member of greater thickness than said free end portion, a hollow sheet metal member having a substantially straight lower portion provided with a lug coöoperating with the lug on said shorter arm and a curved upper portion welded to said short arm, a hub extended through said supporting member and provided with an upwardly tapering bore, and a key carried by said supporting member and extended into said hub.
- 10 2. In a flier, in combination, a solid metal member comprising an arm having a lower portion and a curved upper portion, a supporting member extended from said curved upper portion and a shorter curved arm extended from said supporting member and having its portion near said supporting member of increased thickness, a hollow sheet metal member having a lower portion and a curved upper portion firmly united with said curved shorter arm, and a hub extended through the supporting member of said solid member.
- 15 3. In a flier, in combination, a solid metal member comprising an arm having a curved upper portion, a supporting member extended from said curved upper portion, and a shorter curved arm extended from said supporting member, and a hollow sheet metal member having a curved upper portion firmly united with the shorter curved arm of said solid metal member.
- 20 4. In a flier, in combination, a solid metal member having a curved arm, a hollow sheet metal member having a curved portion welded to the curved arm of said solid metal member and a solid counterbalancing arm for said hollow sheet metal member forming part of said solid metal member.
- 25 5. In a flier, in combination, a solid metal member having a supporting member provided with an opening and curved portions on opposite sides of said supporting member and having a solid substantially straight portion extended from one of said curved portions, a hollow sheet metal member having a curved portion firmly united with the other of said curved portions of said solid member, a hub separate from said supporting member and extended through the opening in the latter, and means for securing said hub to said supporting member.
- 30 6. In a flier, in combination, a solid metal member, a hollow sheet metal member and a solid metal counterbalancing member for said hollow sheet metal member forming part of said solid metal member welded to said solid metal member.
- 35 7. In a flier, in combination, a solid metal member, a hollow sheet metal member and a solid metal counterbalancing member for said hollow sheet metal member forming part of said solid metal member, firmly connected with said solid metal member.
- 40 8. The method of making fliers having a solid metal member and a hollow sheet metal member, which consists in forming a substantially flat supporting member with a hole through it and having an arm of substantially the thickness of the supporting member extended from one side of the latter and having extended from its other side a curved arm of less thickness than the first-mentioned arm and provided with a concaved outer surface, attaching a sheet metal blank in a partially folded condition to the concaved surface of the second-mentioned arm, bending the sides of said blank toward each other to form the hollow sheet metal member, inserting a hub through the hole in the said supporting member, and securing said hub to the latter.
- 45 9. The method of making fliers having a solid metal member and a hollow sheet metal member, which consists in forming the solid member with a substantially long arm having a curved upper portion, a substantially flat supporting member provided with a hole extended through it and of substantially the same thickness as the said curved portion and extended therefrom, and a second curved arm extended from said supporting member and of less thickness than the latter and provided with a concaved upper surface, attaching a sheet metal hollow member to the concaved upper surface of the second curved arm, inserting a hub through the hole in the supporting member, and securing said hub to said supporting member.
- 50 10. The method of making fliers composed of a solid metal member and a hollow sheet metal member, which consists in attaching a sheet metal blank in an opened up condition to the solid metal member and then bending the sides of the blank toward each other to form the hollow metal member and leave a longitudinally extended slot between the edges of said folded sides, and filling the grooves between the hollow sheet metal member and the solid member with a material capable of fusing at a relatively low heat.
- 55 11. The method of making fliers composed of a solid metal member and a hollow sheet metal member, which consists in making the solid member with a supporting member having a hole through it, and with

4

curved arms of unequal thickness extended in opposite directions from said supporting member and with a substantially straight arm extended from the curved arm of 5 greater thickness, overlapping the curved arm of lesser thickness with the sheet metal member, welding the sheet metal member to said latter arm, inserting a hub through the hole in the supporting member and securing said hub to said supporting member.

12. The method of making a flier which consists in forming a solid metal arm with an extension adapted to receive a hub and a further extension adapted to receive the 15 end of a hollow arm, forming a hollow arm out of sheet metal, and welding the end of said hollow arm to said further extension.

13. The method of making a flier which consists in forming a solid metal arm with an extension adapted to receive a hub and a further extension adapted to receive the end of a hollow arm, forming a hollow arm out of sheet metal, welding the end of said hollow arm to said further extension, and 25 inserting a hub in said first-mentioned extension.

14. The method of making a flier which consists in forming a solid metal arm with an extension adapted to receive a hub and 30 a further extension adapted to receive the end of a hollow arm, forming a hollow arm out of sheet metal, inserting a hub in said first-mentioned extension, and attaching the end of said hollow arm to said further extension.

15. In a flier, in combination, a solid metal member having a substantially straight lower portion, a curved upper portion, a substantially straight supporting member having 40 an opening through it, and a second curved portion opposite the first-mentioned

curved portion and provided near its free end with a lug, a hollow sheet metal member having a curved portion firmly united with the second curved portion of the solid 45 member and provided with a lug coöperating with the lug on said second curved portion to form a presser mounting, a hub separate from said supporting member and extended through the opening in the latter, 50 and means for securing said hub to said supporting member.

16. In a flier, in combination, a solid metal member comprising an arm having a curved upper portion, a supporting member 55 extended from said curved upper portion and provided with a shoulder, and a shorter curved arm extended from said supporting member, and a hollow sheet metal member having a curved upper portion firmly united 60 with the shorter curved arm of said solid member and having a finger abutting said shoulder with the upper surface of the finger substantially flush with the upper surface 65 of said shoulder.

17. In a flier, in combination, a solid metal member comprising an arm having a curved upper portion, a supporting member extended from said curved upper portion, a shorter curved arm extended from said supporting member, a hollow sheet metal member having a curved upper portion bearing upon the upper surface of the said shorter curved arm and firmly secured to the latter and forming grooves with the side edges of 70 said shorter curved arm, and means for filling the said grooves to obtain a smooth external surface for the hollow sheet metal member and the said shorter curved arm.

In testimony whereof, I have signed my 80 name to this specification.

EDWARD B. FEASTER.

It is hereby certified that in Letters Patent No. 1,393,356, granted October 11, 1921, upon the application of Edward B. Feaster, of Boston, Massachusetts, for an improvement in "Fliers and Methods of Making the Same," errors appear in the printed specification requiring correction as follows: Page 3, claim 6, lines 70 and 71, strike out the words "welded to said solid metal member," and insert the same to follow the word "member," second occurrence, in line 67; same page, claim 7, lines 76 and 77, strike out the words "firmly connected with said solid metal member," and insert the same to follow the word "member," second occurrence, in line 73; and that the said Letters Patent should be read with these corrections therein that the same may conform to the record of the case in the Patent Office.

Signed and sealed this 27th day of December, A. D., 1921.

[SEAL.]

KARL FENNING,

Acting Commissioner of Patents.
